UNITED STATES PATENT OFFICE.

HARVEY C. SHAMBLIN AND EDWARD E. MCKAY, OF COMMERCE, OKLAHOMA.

LUBRICATING DEVICE.

1,372,253.

Specification of Letters Patent. Patented Mar. 22, 1921.

Application filed July 24, 1919, Serial No. 313,076. Renewed December 27, 1920. Serial No. 433,424.

To all whom it may concern:

Be it known that we, HARVEY C. SHAMBLIN and EDWARD E. MCKAY, citizens of the United States, and residents of Commerce, 5 in the county of Ottawa and State of Oklahoma, have invented a new and Improved Lubricating Device, of which the following is a full, clear, and exact description.

This invention relates to improvements in 10 lubricating devices, and more particularly to a lubricator designed for use with internal combustion engines and the like, in which a partial vacuum causes a suction of air and the air drawn into the engine cylinder is caused to move through the vaporizing chamber to an improved lubricating device to vaporize the lubricant and carry it 15 with the air in the form of a fine spray into the engine cylinder.

20 A further object is to provide an improved means for automatically controlling the level of lubricant in the vaporizing chamber.

25 A further object is to provide improved means for regulating the vacuum necessary to operate the device.

30 A further object is to provide improvements of the character stated in which the entire operation is in accordance with the partial vacuum or movement of air so that 35 the proper proportions of lubricant are provided in accordance with the speed of the engine.

With these and other objects in view the 35 invention consists in certain novel features of construction, and combinations and arrangements of parts, as will be more fully hereinafter described and pointed out in the claims.

40 In the accompanying drawings—

Figure 1 is a view in side elevation illustrating our improvements;

Fig. 2 is a fragmentary view in section on the line 2—2 of Fig. 1;

45 Fig. 3 is an end view; and

Fig. 4 is a view in longitudinal vertical section.

1 represents a supply tank and 2 a vaporizing chamber below the tank and secured 50 thereto by means of screws 3 or other connecting devices. The tank 1 has an inlet 4 in its top normally closed by cover plates 5, and an air inlet pipe 6 communicates with one end of the vaporizing chamber 3, the latter preferably having an inclined lower wall 2", as clearly shown in Fig. 4.

In the air inlet pipe 6 a controlling valve 7 is located fixed to a stem 8, the latter projecting upwardly through a casing 9. A coiled spring 10 in the casing 9 exerts downward pressure on the valve stem tending to open the valve, and a winged nut 11 screwed on to the upper end of the stem regulates the spring pressure, while a screw abutment 12 is provided below the valve to limit its 60 opening movement. This valve 7 is opened by a suction of the partial vacuum caused within the engine cylinder and does not open until the pressure of the spring 10 is overcome. This pressure can be varied by the 65 adjustment of the winged nut 11, as will be readily understood.

The lubricant from tank 1 into the vaporizing chamber 2 is supplied by means of a feed device 13, which may be of the sight 75 feed variety, if desired. This feed device 13 is connected by a cock 14 with tank 1 and by a T-coupling 15 with an inlet pipe 16 extending into the vaporizing chamber 2.

An ordinary pet cock 17 is located at the 80 lower end of the feed device as shown. A check valve 18 in pipe 16, engaging a valve seat 19 therein, is normally held in closed position by means of a float 20 supported in the lubricant 27, but when the lubricant falls 85 below the desired level, the valve 18 will open to admit the lubricant to bring the level up to normal. An outlet passage 21 communicates with the vaporizing chamber 2 and is separated therefrom by a wall 22 extending below the liquid level in the vaporizing chamber and constituting in effect a trap, as clearly shown in Fig. 4. A check valve 23 permits a flow in one direction only 90 through the passage 21 and a screw plug 24 is located above the check valve 23 and permits access thereto when desired. The outlet passage 21 is connected by any ordinary pipe 25 with the cylinder 26 with the engine. 95

The operation is as follows: When the engine piston moves away from the cylinder head, it creates a partial vacuum in the cylinder and sucks air through the pipe 25 and passages of our improved device, as will now be explained. The suction of air causes 105 the valve 7 to open and admits the air into the vaporizing chamber 2, and thence over the surface of the lubricant, the wall 22 compelling a close contact of the air with the lubricant. This compels the lubricant to be 110 vaporized so that it escapes through the outlet 21 in the form of a spray or vapor

thoroughly commingled with the air so that it is evenly distributed over all the surfaces of the cylinder and piston to insure a thorough lubrication.

5. It will be noted that the quantity of lubricant is controlled by the vacuum or movement of air. Hence, when the engine is running slowly, the supply of lubricant will be appreciably less than when the engine is 10 running rapidly. There will result an economy in lubricant and also a more perfect lubrication of parts in accordance with necessity.

Various slight changes may be made in 15 the general form and arrangement of parts described without departing from the invention, and hence we do not limit ourselves to the precise details set forth but consider ourselves at liberty to make such changes 20 and alterations as fairly fall within the spirit and scope of the appended claims.

We claim:

1. A lubricating device of the character described, comprising a supply tank, a vaporizing chamber, a feed mechanism connecting the tank with the vaporizing chamber, means for maintaining a uniform level of lubricant in the vaporizing chamber, an outlet passage for said vaporizing chamber, 30 one wall of said passage projecting into the lubricant and forming a trap, and a check valve in said outlet passage.

2. A lubricating device of the character described, comprising a supply tank, a vaporizing chamber below the same, a feed device connecting the tank and vaporizing chamber, a float valve in the vaporizing chamber controlling the admission of lubricant thereto, said chamber having an inlet 40 at one end and an outlet at its other end,

a check valve in said outlet, and a wall separating the outlet from the vaporizing chamber and extending below the level of lubricant in the vaporizing chamber.

3. A lubricating device, comprising a 45 vaporizing chamber adapted to contain lubricant, an air inlet passage communicating with said vaporizing chamber, a spring held suction operated valve in said inlet passage, an outlet passage for said vaporizing chamber, one wall of said passage projecting into the lubricant and forming a trap, and a check valve in the outlet passage.

4. A lubricating device of the character described, comprising a supply tank, a 55 vaporizing chamber below the tank and communicating therewith, a float valve in the vaporizing chamber controlling the level of the lubricant therein, said vaporizing chamber having an inlet at one end and an outlet 60 at its other end and one wall of said passage projecting into the lubricant and forming a trap, a check valve in said outlet, and a screw plug located in the upper portion of the chamber above the check valve. 65

5. A lubricating device of the character described, comprising a supply tank, a vaporizing chamber below the supply tank and communicating therewith, said vaporizing tank having an inclined bottom tapering 70 downwardly from its inlet to its outlet end, a float valve in the vaporizing chamber controlling the level of lubricant therein, said vaporizing chamber having a valved inlet and a valved outlet in its respective ends, 75 and a wall at the outlet end of the chamber projecting into the lubricant to form a trap.

HARVEY C. SHAMBLIN.
EDWARD E. MCKAY.
